(57) CLAIM

We claim the ornamental design for an exercise garment, as shown and described.

DESCRIPTION

FIG. 1 is a front perspective view of my design for a exercise garment having an outer layer and an under layer, and a waist foldover.

FIG. 2 is a front view thereof.

FIG. 3 is a rear view thereof.

FIG. 4 is a left side view thereof.

FIG. 5 is a right side view thereof.

FIG. 6 is an enlarged top view thereof.

FIG. 7 is an enlarged bottom view thereof; and,

FIG. 8 is a cross-sectional view along line 8-8 shown in FIG. 6 thereof.

In FIG. 1, the broken lines represent the feet of a wearer, and represent matter that is not claimed herein.

1 Claim, 6 Drawing Sheets
